GARMENT-PRESSING MACHINE.

1,117,037.

Specification of Letters Patent. Patented Nov. 10, 1914.

Application filed July 17, 1913. Serial No. 779,428.

To all whom it may concern:

Be it known that I, DAVID C. HALE, Jr., a citizen of the United States, residing at Cincinnati, in the county of Hamilton and State 5 of Ohio, have invented certain new and useful Improvements in Garment-Pressing Machines; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 My invention relates to an improved machine for pressing garments. Primarily, the object of the invention is to bring such a machine within the reach of all those who do the work of cleaning and 20 pressing garments, whether they be the larger or smaller establishments; who do exclusively a garment cleaning and pressing business, or the clothier who cleans and presses garments as an incident of the cloth- 25 ing business. It is well understood by those familiar with this class of work that the application of steam to the garment while being pressed is necessary in order to prepare the fabric and make it more susceptible to 30 pressure to be applied. It is not desirable, however, to apply the steam in a way that will impart to the garment excessive moisture, for the reason that the effect of the 35 pressing will not be lasting; in other words, the garment being given too much moisture while being pressed, when it becomes dry the effect of the pressing becomes less apparent. It will, therefore, be understood that steam is necessary in the operation of 40 pressing garments, and in the proper quantities and at the proper time. Heretofore, it has been the practice in garment pressing machines to furnish the presser head of the machine with steam from the well known 45 source of steam generation, i. e., a boiler. In other words, a steam plant is necessary to prepare the steam for the machine to which it is conducted through piping and valves. Owing to this necessity of supply- 50 ing steam in this manner, garment pressing machines of the most desirable type are

practically not within the reach of any but the larger drying and cleaning establish- 55 ments. This is because of the fact that the maintenance and management of a boiler, and those things that are essential to steam generation by means of a boiler, require knowledge of steam more or less, a knowl- 60 edge that is not possessed by the average person. In a word, it requires the knowl- 65 edge of a steam engineer.

It is, therefore, one of the main objects of my invention to dispense with the use of a boiler as a means for generating steam to be used in a garment pressing machine. In 65 thus dispensing with the usual method of furnishing steam for such machine, many advantages are obtained, to-wit, the machine is available and within the reach of both the small and large concerns engaged 70 in the cleaning and pressing business, as well as the individual; and further, the steam is generated within an element of the pressing machine and in quantities for im- 75 mediate use by means which requires practically no knowledge that is necessary to be possessed by those operating a garment pressing machine and a boiler as an essential accompaniment; and further, the element of danger that attends the operation of all 80 boilers is eliminated and the consumption of water is correspondingly curtailed.

A further object of the invention is to pro- 85 vide means for supplying flashes of steam to the garment as the latter is being subjected to the pressing operation. This is done through means of a presser head which is adapted to be electrically heated and to receive three degrees of electrical heat, and is adapted for the instantaneous generation 90 of heat within it, thereby obviating the old method of supplying heat from a boiler, which must be maintained at a degree of temperature corresponding to steam pres- 95 sure of approximately 60 lbs. and which must be super-heated after its introduction to the presser head. As a concomitant of the pressing machine, a wafer pump is conveniently arranged to supply to the presser head, intermittently, at greater or less inter- 100 vals depending upon the character of the garment, a supply of water which is instant-

taneously transformed into steam within said head and is flashed against the surface of the garment.

In preparing the machine for the work, the higher voltage current is turned into the head and it is quickly brought to a sufficient temperature for operative purposes. After the head is thus given a proper temperature, the lower voltage current may be switched into the head which is sufficient to maintain the temperature at the desired point. It will thus be seen, by the use of electricity as a heating medium and by dispensing with the usual boiler, a safe machine is provided and one which may be left indefinitely by the operator with no fear of disastrous results.

I have ascertained from extensive experiments that the best results are obtained by producing the steam in quantities for the immediate use and flashing it as the pressing elements impact one with the other with the garment between them.

Referring to the accompanying drawings of my improved garment pressing machine, Figure 1 is a side elevation of the machine, with the table appearing in section; Fig. 2 is a front elevation of the machine; Fig. 3 is a bottom plan view of the presser head with part of the perforated plate removed to show the interior construction and arrangement thereof; Fig. 4 is an enlarged sectional view on the line *a—a* of Fig. 3; Fig. 5 is a sectional view on the line *b—b* of Fig. 3; Fig. 6 is a sectional view on the line *c—c* of Fig. 3; Fig. 7 is a top plan view of the machine as seen from below the table; Fig. 8 is a front elevation of the table; Fig. 9 is a rear elevation of the water pump and reservoir which supplies the water to the presser head; Fig. 10 is a sectional view of the means for regulating the stroke of the pump handle, the section being taken on the line *d—d* of Fig. 1; Fig. 11 is a detail perspective view of one of the presser head tubs which is instrumental in flashing the steam within the presser head; Fig. 12 is a perspective view of one of the jet tubes within the presser head through which the water and steam is distributed to the flashing tubes; Fig. 13 is a detail sectional elevation of a slight modification in the presser head; Fig. 14 is a detail plan view of the electric switch.

In a detail description of the invention, similar reference characters indicate corresponding parts.

Referring more particularly to the drawings, 1 represents a standard provided on its opposite sides with vertical guides 2. Slidingly mounted upon the guides 2 is a standard frame 3 having tracks 4 upon which shafts 5 are adapted to roll. The shafts 5 are provided with grooves 6 near their ends which are received by the tracks

4 and to thereby hold the shafts in position against lateral movement. Mounted on the shafts 5 are grooved rollers 7 which receive rails 8 on the lower side of a table 9. The table 9 is provided with extensions 67 hinged at 68 and supportable in elevated positions by brackets 69 pivoted at 70 and provided with notches 71 adapted to receive pins 72 on the lower end of brackets 73 extending from the lower side of the table. The table 9 is also provided with a shield or guard 74 which is instrumental in preventing the garments coming in contact with the arm 32. The table 9 may be moved horizontally, the rollers 7 and shaft 5 forming a frictionless roller carriage for the same. The shafts 5 are provided with a frame 10 which holds the shafts in their proper parallel position. The standard frame 3 is provided with front and rear stops 11 which engage the frame 10 and limit the horizontal in and out rolling movement of the table 9. The table 9 is provided with a handle or rail 12 by which the operator moves it in and out, and said table 9 is also provided with guards 13 terminating in flanges 14 adapted to engage the lower sides of the tracks 4, thereby preventing any tilting of said table. Mounted on said table is a standard 26 which rigidly supports a buck 27. In placing the garment to be pressed upon the buck, the table is moved out, as shown in Fig. 1, away from the presser head, presently described, to enable the operator to do the preparatory work of placing the garment in position without having to place his face and hands in close proximity to the heated presser head.

After the garment has been properly placed on the buck, the table is moved in by the operator grasping the rail 12, and the buck 27 is brought to a position below the presser head as shown in dotted lines, Fig. 1, from which position the table and therewith the buck may be elevated to press the garment. The table 9 and therewith the frame 3 and buck 27 are elevated and lowered by the following system of levers. Attached to the upper end of the frame 3 is a cross-member 15 having a down projection 16 to which a link 17 is attached. The lower end of the link 17 is pivotally connected at 18 to one end of a lever 19 fulcrumed at 20 to a fulcrum link 21. The lever 19 is provided with a weight 22 which counterbalances the weight of the table 9 and frame 3 during the vertical reciprocating movement thereof. Fulcrumed at 23 to the standard 1 is a foot lever 24 pivotally connected to the lever 19 at a point 25 which is intermediate of the pivot 18 and fulcrum 20. When the outer end of the lever 24 is depressed by the foot of the operator, the link 17, frame 3 and table 9 will be elevated, and when the lever 24 is released, the weight of the parts

17, 3 and 9 will depress the same. The presser head is electrically heated and is constructed and arranged to flash steam to impart to the garment sufficient moisture 5 which is instantly dried in the pressing operation. The presser head is amply illustrated on sheet 3 of the drawings, and consists of a frame 28 provided with apertured bosses 29 on the upper side thereof which 10 receive trunnions 31 of a cross arm 30. The cross arm 30 is part of an overhanging arm 32 the lower end of which is secured to and extends from the standard 1. It will, therefore, be seen, that the presser head is stationary, but, owing to its connection with the overhanging arm 32, it has sufficient movement to permit it to properly engage the buck, when the two are brought together by elevating the buck in the manner described. The arm 32 extends laterally from the base standard 1 and thence upright with the upper end thereof overhanging and in alignment with the vertical axis of said base 1. The presser head 45 is swiveled at its 25 center to the overhanging end of said arm and when the buck is raised against it the said head will, owing to its swiveled connection, properly adjust itself to the buck. Owing to the overhanging extension of the 30 arm 32 being arranged as described, the swiveled presser head 45 is maintained in line with the line of pressure exerted upon it when the buck is elevated against it.

The interior of the presser head frame 28 is provided with longitudinal flanges 33 which provide channels in which tubes 34 are mounted. The said tubes are provided with a series of orifices 35 in the upper sides thereof. Mounted within the tubes 34 are 35 inverted U-shaped channel members 36, the sides of which do not extend to the bottom of the tubes 34. Placed within the channel members 36 and supported by passing through a series of plates 37, are pipes 38. The pipes 38 are provided with apertures 39 along their upper sides through which water is injected into the channel members 36. The water is supplied to ends of the 45 pipes and the size and position of the openings 39 may be varied to secure an equal distribution thereof throughout the lengths of said pipes. The presser head is heated to provide pressing heat and the several channel members are heated to convert the water 50 into steam during the process of pressing, by heating the units 40 which lie against the under sides of the tubes 34. The heating units 40 are provided with heads 41 from which leads 42 extend through which said 55 units are heated, see Fig. 6. The leads 42 connect with a switch 43 the base 44 of which is attached to the top shield 45 of the presser head. The said switch is in turn connected with any suitable form of socket 60 46 also mounted on the base 44. The water

70 pipes 38 are connected to a manifold 47 at one end of the presser head, see Fig. 5, which manifold is connected to a supply pipe 48 lying between the members 28 and 45 of the presser head. The pipe 48 extends out of the top of the presser head and connects with a swivel joint 49 on the outside of said presser head and in axial alignment with the pivot 31 and the cross arm 30. The swivel joint 49 is connected with a pump 50 of any suitable well known construction by a tube 51. The pump 50 is supported by a reservoir 52 mounted on the arm 32 in suitable proximity to the presser head and in a position free from interference with the operation of the machine. The plunger 53 of said pump is attached to and actuated by a hand lever 54, fulcrumed at 55 to an arm 56 extending from said pump to within convenient reach of the operator. The lever or pump handle 54 extends through a slotted member 57 which contains a spring 58, shown in Fig. 10, which is instrumental in moving the pump handle to an elevated position. The member 57 is provided with an adjustable collar 59 by means of which the stroke of said handle and the plunger 53 may be regulated. The pump is provided with a suction pipe 60 having a check valve 61 and connecting the pump and the reservoir in a well known manner. When the pump is operated, water will be delivered to the presser head to suit the purposes. The water is discharged into the pipes 38 and against the upper inner faces of the 90 channel members 36. The temperature of the water is raised to a very appreciable degree as soon as it enters the pipes 38 and when discharged therefrom it falls by gravity to the bottom of the tubes 34 where its 95 temperature is raised by the heat units 40 until the water is transformed into steam or in a form of moisture approximating steam suitable for the pressing process. The steam escapes from the tubes 34 through the orifices 35 therein and is conducted downward by the flanges 33. The steam then dashes through a perforated plate 62 attached to the under side of the presser head. The perforated plate 62 presents a plain 100 surface which is covered with a suitable pressing cloth 64. The perforated plate 62 is made sufficiently rigid by projections 63 a suitable number of which extend from the lower side of the presser head frame 28. 105 The lower face of said perforated plate 62 is covered by suitable cloth 64 which is held in position by bars 65 which lie within a circumferential groove 66 in the presser head frame 28. The bars 65 engage the 110 edges of the fabric 64 within the groove 66 and maintain said cloth taut through friction. The space between the presser head frame 28 and the top or shield 45 thereof 115 may be filled with any suitable insulating 120 material. The base 44 of the presser head 125

material, such as mineral wool or asbestos which is instrumental in minimizing heat radiating from the top of the presser head.

Light may be had whenever desired, for this purpose a bracket 75 extends from the arm 32 and supports a reflector 76 which may receive a suitable incandescent lamp, not shown. The reflector 76 is in position to direct the light from the lamp upon the 10 garment on the buck 27 when the table is in its outermost position.

The operation of my device is as follows: When the operator places the garment upon the buck 27, the table is in its outermost position. He then moves said table inwardly to a position where the buck 27 comes directly under the presser head. He then elevates the table and brings the buck and the garment thereon in contact with the 20 presser head, sufficient force being applied to press the garment. When the buck with the garment thereon is in contact with the presser head, the pump lever 54 is operated to discharge a suitable quantity of water 25 into the presser head to supply the garment with sufficient steam moisture which is necessary to the process of pressing. When the garment has been subjected to heat and pressure a sufficient length of time to relieve the 30 garment of any moisture due to the flash of steam, the buck and table are lowered by releasing the lever 24 and said buck and table may be moved outwardly to rearrange the garment.

35 By providing a horizontally and vertically movable table and buck, no portion of the machine forms an obstruction to the hands of the operator when placing the garment upon the buck. Danger of the hands 40 coming in contact with the heated presser head is eliminated. It is to be also understood that the heat for pressing is not supplied by the moisture or steam; that the temperature of the pressing head may be 45 considerably higher than the temperature of the steam, thus more effectually pressing the garment through the elimination of any moisture therefrom which would otherwise leave the garment in a limp condition. It 50 will also be noted that as the steam must traverse an irregular path before coming in contact with the garment, no liquid may escape from the tubes 34 without being converted into steam, thereby preventing the 55 garment becoming wet.

In Fig. 13, an asbestos sheet 61^a is shown interposed between the pressing cloth 64 and the perforated plate 62 as a precautionary means to prevent the pressing cloth from 60 being scorched by the heat. Inasmuch, however, as complete control is had by the operator over the heating appliance, the scorching or burning of said cloth is not likely to occur. The heat may be regulated 65 by means of the switch shown in Fig. 14.

While I have with much particularity set forth the structure of the apparatus, I do not wish to be limited to structural features which are not vital, as it is well known that these may often be varied by the skill of the 70 mechanic without departing from the spirit and underlying principles of the invention which briefly may be said to comprise a garment pressing machine in which the buck has a vertical and horizontal movement and 75 the presser head has a capacity for generating steam.

1. claim.

1. A presser head, comprising a channeled plate, a cap united to said plate, and 80 a perforated plate attached to said channeled plate, telescopic steam generating members within the channels of said plate, a heating unit for the outermost one of said telescopic members, and water pipes inclosed within 85 the innermost telescopic members and adapted to discharge water to the outermost telescopic members, and electrical means for heating said units.

2. In a presser head, a frame having longitudinal flanges, tubular members mounted between said flanges, means for heating said tubular members and frame, channel members mounted in said tubular members and having outlets to said tubular members, 95 and means within said channel members for supplying liquid to said tubular members, whereby moisture in the form of steam may be generated at a temperature lower than that of the tubular members and frame. 100

3. In a presser head, a frame having longitudinal flanges, tubular members having openings at the upper portion of their sides mounted between said flanges, channel members mounted within said tubular members, 105 means for heating said tubular members and said frame, perforated tubular members mounted within said channel members and adapted to supply liquid to said tubular members, whereby moisture in the form 110 of steam is generated within said tubular members at a temperature lower than that of the frame and tubular members.

4. In a presser head, a frame having longitudinal flanges, rectangular tubular members having openings in the upper portions of their sides mounted between said flanges, means for heating said frame and tubular members, channel members mounted within said tubular members, perforated tubes 115 mounted within said channel members, and adapted to direct and discharge liquid therefrom against the upper portion of said channel members, and means adapted to supply liquid to said perforated tubes. 120

5. In a garment pressing machine a base, a standard extending laterally therefrom and thence vertically and terminating in an overhanging arm the end of which lies in a plane with the vertical axis of said base, 1

a presser head having a longitudinal swiveled connection with the overhanging end of said arm, a water pipe having a swiveled connection with said presser head in alignment with the connection between the presser head and the arm, a vertically movable frame mounted on said base, a table supported on said frame, a buck mounted on said table and adapted to be elevated in

a plane with the vertical axis of the base to 10 engage the presser head, substantially as specified.

In testimony whereof I affix my signature, in presence of two witnesses.
